US00D857337S

(12) **United States Design Patent** (10) **Patent No.:** **US D857,337 S**
(45) **Date of Patent:** **** Aug. 27, 2019**

(54) **GARMENT BOTTOM**

(71) Applicant: **Under Armour, Inc.**, Baltimore, MD (US)

(72) Inventors: **Merida Miller**, Baltimore, MD (US); **Nicole Parisi**, New York, NY (US); **Elyse Alligood**, New York, NY (US); **Jeanne Foley**, New York, NY (US)

(73) Assignee: **UNDER ARMOUR, INC.**, Baltimore, MD (US)

(**) Term: **15 Years**

(21) Appl. No.: **29/663,817**

(22) Filed: **Sep. 19, 2018**

Related U.S. Application Data

(63) Continuation of application No. 29/629,423, filed on Dec. 13, 2017, now Pat. No. Des. 831,304, which is a continuation of application No. 29/612,126, filed on Jul. 28, 2017, now Pat. No. Des. 808,122, which is a continuation of application No. 29/597,999, filed on Mar. 22, 2017, now Pat. No. Des. 796,152, which is a continuation of application No. 29/555,729, filed on Feb. 24, 2016, now Pat. No. Des. 783,937.

(57) **CLAIM**

The ornamental design for a garment bottom, as shown and described.

DESCRIPTION

FIG. 1 is a rear perspective view of a garment bottom showing our new design;

FIG. 2 is front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken dashed line illustration in the drawings is not part of the claimed design.

1 Claim, 4 Drawing Sheets
